Attorney.

UNITED STATES PATENT OFFICE

2,386,489

CARRIER

Archibald D. McKellar, Park Ridge, Ill.

Application February 18, 1942, Serial No. 431,336

5 Claims. (Cl. 206—16)

The invention relates to improvements in carriers, but more particularly to devices of this character which are arranged and adapted to support and hold a portable suction cleaner in operative position and to facilitate the movement of such a device and its attendant accessories from place to place, and has for its objects the provision of a device of this character which will be simple in construction, economical to manufacture, and highly efficient in use.

A further object of the invention is to provide a device of this character upon which a portable suction cleaner and its attendant accessories or attachments may be easily and quickly mounted in such manner and in such positions as will effectively adjust the center of gravity toward increased stability.

Another object of the invention is to provide a device of this character upon which a portable suction cleaner and its attendant accessories or attachments may be mounted in such manner and in such positions as will effectively resist any forwardly rotary motion occurring when a suction hose is attached and when such hose is used as a means of pulling the suction cleaner from place to place as necessity requires.

Other objects will hereinafter appear.

The invention consists in the combinations and arrangements of parts hereinafter described and claimed.

The invention will be best understood by reference to the accompanying drawing forming a part of this specification and in which:

Figure 1 is a plan view of such a device embodying the invention;

Figure 2 is a front elevation of the embodiment of the invention having portions cut away to better illustrate its construction;

Figure 3 is a section taken substantially on line 3—3 of Figure 2, and by broken line insertions illustrates the device in use with a particular type of suction cleaner; and

Figure 4 is a section taken substantially on line 4—4 of Figure 3.

The practical embodiment of the invention, illustrated in the aforementioned drawing, is formed from suitable sheet metal portions arranged in position and joined, preferably by welding in the usual manner, into an integral body 10, best shown in Figures 2, 3, and 4. The body 10 comprises an elliptical like base plate 11, the rearward part of which is arranged horizontally, and a forward part 12 inclined upwardly and outwardly therefrom, the purpose of which will be hereinafter more particularly set forth.

A curved wall plate 13 is arranged vertically upon the base plate 11 at its rearward edge, and a low rim 14 is similarly arranged upon the forward portion 12 of the said base plate 11. The curved wall plate 13 and the low rim 14 are united at their junctures to form a continuous wall around the perimeter of the elliptical base plate 11, as is best shown in Figures 1, 3, and 4. A flat partition 15 is arranged vertically upon the base plate 11 in chordal position with the curved wall 13. By this arrangement, a compartment 16 is provided and the structure made substantially rigid by the D shaped tubular arrangement. The partition 15 is provided with a hand-hole 15a adjacent its top (Figure 2) to facilitate the lifting of the empty carrier, if and when desired. A partition 17 having angularly disposed side flanges 18, of lesser height than the partition 15 and the curved wall 13, is arranged vertically within the compartment 16 upon the base plate 11, as best shown in Figures 1, 3, and 4. The side flanges 18 are attached as shown to the inner side of the curved wall 13, as shown. The position of the partition 17 divides the compartment 16 at its bottom into separate compartments 19 and 20, best shown in Figures 1 and 2. The compartment 19 is adapted to receive sections of wand tubing E, and the compartment 20 suitable for the coiled hose H. In regard to the compartments 16, 19, and 20, it is to be noted, that the arrangement is such, that the upper part of compartment is sufficiently large to accommodate connecting parts of both wand tubes E and the hose H which are usually larger than the wand tubes and hose proper, thus affording a more compact storage space for the whole.

As shown in Figures 1, 2, and 3, an L shaped partition 21 is arranged in horizontal position forwardly of the partition 15 adjacent the upper edge thereof. The ends of the said partition 21 are attached to the curved wall 13 and the lower and rearward edge thereof to the partition 15. By this arrangement, a compartment 22 is provided which is adapted to receive and retain atomizers A commonly used in connection with suction cleaners. The partition 21 is provided with a suitable slot 23 at its lower rearward portion adjacent the partition 15, best shown in Figures 1 and 3, which is adapted to hold in vertical position an envelope or folded filter papers F used in suction cleaners of certain types. An angular partition 24 is arranged forwardly of the partition 21 in horizontal position, its ends being secured to the curved wall 13, and its bottom rear edge to the vertically arranged part 26

of the partition 21. The partition 24 is provided with inverted cup-like hand-hold 24a in its bottom (Figure 3) which is suitably located for lifting a fully loaded carrier. A compartment 25 is provided by this arrangement of the partition 24 which is adapted to hold a felt pad or floor tool T.

A partition 27 is mounted between the base plate 11 and the partition 21 projecting outwardly and upwardly from the vertical partition 15, as best shown in Figure 3. By this arrangement a compartment 28 is provided for nozzles, brushes or the like and the compartment 25 shielded from the heated air discharged by the suction cleaner.

A curved wall plate 29 is secured across the inner portion of the base plate 11 substantially concentric with the low rim 14 and forming with said rim 14 a socket 14a adapted to receive a suction cleaner C in operative position, as best shown in Figure 3. The curved wall 29 extends upwardly from the base plate 11 to approximately the top of the suction cleaner base C and is held in position by outwardly projecting side flanges 30 secured to the curved wall 13, and best shown in Figure 4. By this arrangement the two compartments 31, the location and shape of which are best shown in Figures 2 and 4, are provided. These compartments 31 are particularly adapted for the storage of fragile containers of fluids for the atomizer A. A flexible pad 32 lines the inner side of the rim 14 and is held in position by having its ends inserted in suitable recesses 33 (Figure 4).

Referring to Figure 3 particularly, it is to be noted and understood that the can type of suction cleaner C, indicated by broken lines, has its center of gravity substantially at the axial line of the vertically arranged motor which is mounted just below the blower connection B, and that this axis is at right angle to the bottom of the cleaner can C. As is hereinbefore mentioned, the forward portion 12 of the base plate 11 is inclined upwardly and forwardly therefrom, substantially as shown in Figures 2 and 3. The arrangement is such that the forward part of the bottom of the cleaner can C, which is just below the suction inlet S, rests on the upper and forward edge of the said forward portion 12 with the forward wall of the said cleaner can C against the pad 32 for approximately one-half of the circumference thereof. The cleaner can C is arranged just forwardly of the curved wall 29 which is arranged concentrically with the forwardly part of the rim 14 and extends upwardly sufficiently to contact an upper and rearmost portion of the cleaner can C. By this arrangement, the weight of the cleaner C is sufficient to wedge and frictionally hold the can C in the socket 14a. The cleaner can C may be easily removed, if and when desired, by lifting on its bale at B.

Portable suction cleaner devices of the type shown in broken line in Figure 3 are usually dragged from place to place as necessity requires during the cleaning operation by pulling on the hose H attached by a suitable connection to the suction inlet S, as indicated. With the hose H connected at this point the center of gravity is moved forward of the vertical axis of the motor due to the weight of the hose H and the amount of pulling force exerted. It can readily be seen, that considerable skill and no little attention may be required of an operator, under certain conditions, to keep the cleaner upright and in operative position, lest a sudden pull on the hose bring

the center of gravity forwardly of the point of support and an unstable equilibrium be established. As before mentioned, the center of gravity of the empty carrier is approximately below the hand-hole 15a in the partition 15, and of the loaded carrier approximately in line with the hand-hold 24a in the partition 24, and best shown in Figures 2 and 3. Inasmuch as the center of gravity of the loaded carrier is located rearwardly of that of the cleaner, itself, the removal or exchange of the attendant accessories does not interfere with the pivoting of the carrier on the rearward and horizontal portion of the base plate 11. The point of pivoting of the loaded carrier is located approximately on the long diameter of the base plate 11 and below the hand-hold 24a. The arrangement is such, that when a side pull is exerted by the hose H, this pivoting will allow the carrier to swing around so that a direct forward movement is obtained and the whole assembly stabilized thereby. The upwardly and forwardly inclined portion of the base plate 11 affords a sled like means which allows the carrier to be readily moved over slight obstructions during such moving.

In the foregoing specification and the drawing forming a part thereof, I have illustrated and described practical elements of embodiment of my invention which are capable of alteration, variation and modification in structure and arrangement without departing from the spirit of my invention. I, therefore, do not wish to be limited by the precise details set forth therein, but desire to avail myself of such variations and modifications as fall within the scope of the following claims.

I claim:

1. A device of the character described comprising an oblong base plate; a low rim secured around one end of said base plate; a curved wall secured across the inner portion of the said base plate and forming with said rim a socket for the reception of a suction cleaner in operative position of use; a second curved wall plate secured around the other end of said base plate, substantially parallel to the first mentioned wall plate, and forming therewith a space for the reception of attachments for the said suction cleaner.

2. A device of the character described comprising an oblong base plate; a low rim secured around one end of said base plate; a curved wall secured across the inner portion of the said base plate and forming with said rim a socket for the reception of a suction cleaner in operative position of use; a second curved wall plate secured around the other end of said base plate, substantially parallel to the first mentioned wall plate, and forming therewith a space for the reception of attachments for the said suction cleaner; and a vertical partition arranged in the receiving space between said walls.

3. A device of the class described comprising an oblong base plate; a low rim secured around one end of said base plate and forming with said rim a socket for the reception of a suction cleaner in operative position of use; and a second curved wall plate secured around the other end of said base plate, substantially parallel to the first mentioned wall plate; and forming therewith a space for the reception of attachments for the said suction cleaner; the base plate being bent to cause the portion thereof under the said socket to be elevated from the supporting surface.

4. A device of the class described comprising an oblong base plate; a low rim secured around one end of said base plate; a curved wall plate secured across the inner portion of the said base plate and forming with said rim a socket for the reception of a suction cleaner in operative position of use; a second curved wall plate secured around the other end of said base plate, substantially parallel to the said first mentioned wall plate and forming therewith a space for the reception of attachments for said suction cleaner; a vertical partition arranged in the space between said curved wall plates; and in which the space between said partition and that over the socket is divided into a plurality of separate compartments.

15

5. A device of the class described comprising an oblong base plate; a low rim secured around one end of said base plate; a curved wall secured across the inner portion of the said base plate and forming with said rim a socket for the reception of a suction cleaner in operative position of use; a second curved wall plate secured around the other end of said base plate, substantially parallel to the first mentioned wall plate, and forming therewith a space for the reception of attachments for said suction cleaner; a vertical partition arranged in the space between said walls; and a lifting handle in said partition.

ARCHIBALD D. MCKELLAR.
